UNITED STATES PATENT OFFICE.

MAX NYDEGGER, OF ELIZABETH, NEW JERSEY.

KNITTED GARMENT.

1,072,640.

Specification of Letters Patent. Patented Sept. 9, 1913.

Application filed May 2, 1912. Serial No. 694,631.

To all whom it may concern:

Be it known that I, MAX NYDEGGER, a citizen of Switzerland, and resident of the city of Elizabeth, county of Union, and State 5 of New Jersey, have invented an Improvement in Knitted Garments, of which the following description, in connection with the accompanying drawings, is a specification, like letters on the drawings representing like 10 parts.

The present invention relates to an improvement in the manufacture of knitted garments and has to do more particularly with the class of garments comprising 15 sweaters, sweater vests and knitted coats.

The object has been to produce a garment in which the amount of hand work is reduced to a minimum.

Heretofore the pockets in knitted garments have usually been provided by cutting an opening in the fabric and splicing in by hand a previously knitted pocket. The present invention, however, contemplates the knitting of the body of such a garment 20 and the pockets in a continuous operation so that at no time during the forming of the garment is the continuity of the knitting interrupted, the improved product described in this specification being illustrated in the 25 accompanying drawings forming a part hereof, of which,

Figure 1 is a perspective view of a sweater embodying the improved construction of pockets. Fig. 2 is a detail section of 30 the same along the line 2—2 of Fig. 1 and partly in perspective. Fig. 3 is a front elevation of a straight needle plate adapted for use in knitting the improved sweaters. Fig. 4 is a detail plan view of a cam box adapted 35 to operate therewith, and Figs. 5 and 6 are longitudinal and cross sections of the cam box along the lines 5—5 and 6—6 respectively.

Referring now to the drawings, particularly Figs. 1 and 2, a sweater *a* is shown with a part of the inner side exposed. The knitting process involved in producing such a sweater begins at the bottom *h* and is followed in the well known manner to a point 50 indicated by the line *g—g* which also marks

and coincides with the outer edge *c* of the pocket slit. The continuity of the body portion of the garment is then interrupted while the operation of knitting the pocket forming strip *b* continues until the strip becomes sufficiently long to form, when folded, the walls of a pocket having selvage edges *d* and *e*. The knitting of the whole width of the garment is then resumed from the line *g—g* where it was interrupted. The edge *d* and *e* of the strip *b* may then be joined together when desired in any suitable fashion to close the sides of the pocket.

The important advantage in knitting garments according to the present invention is 65 that the whole body of the garment is knitted in one continuous operation and on one machine. This machine is the ordinary straight bed knitting machine except that a special cam moving mechanism has been 70 provided to adapt the cam box for use in connection with a novel arrangement of needles.

Referring to Fig. 3 of the drawings, a portion of the needle plate 1 is fitted with 75 needles 2 having longer butts than the others. The cams 3 and 4 shown in Fig. 5 act in the well known manner upon all of the needles, engaging with the butts thereof as the cam box traverses the needle plate. 80 When however, it is desired to knit only the pocket portions of the garment, the cam plate 5 is elevated by means of a slidable rod 6, which engages slots 7 in plunger 8, attached to the said cam plate, thus causing 85 the cams to engage only the long butt needles 2 and to pass clear of the short butt needles 9 without causing them to be actuated. This shifting from the low position to the higher position of the cam plate may 90 be effected without stopping the machine and without interrupting the continuity of the knitting of the fabric. When the pocket portion has been knitted, the slidable rod is pushed again into normal position thus lowering the lock plate or cam plate so that the cams again engage all of the needles and cause the knitting of the garment to be resumed across its entire width. Obviously 95 the width of the pocket portion or portions 100

may be determined by the number of high butt needles inserted in place of corresponding low butt needles and the pockets may be formed at any desired place in the fabric or 5 at any number of different places.

I claim as my invention:—

In a knitted body garment, an interior pocket comprising a looped strip knitted at each end continuously with the garment, the

side edges of said strip being joined together.

In testimony whereof, I have signed my name to this specification, in the presence of two subscribing witnesses.

MAX NYDEGGER.
